UNITED STATES PATENT OFFICE.

WILLIAM H. WIX, OF BALTIMORE, MARYLAND.

AUTOMATIC OIL-FEED DEVICE.

1,418,046.

Specification of Letters Patent. Patented May 30, 1922.

Application filed July 14, 1920, Serial No. 396,214. Renewed January 21, 1922. Serial No. 531,000.

To all whom it may concern:

Be it known that I, WILLIAM H. WIX, a citizen of the United States, residing at Baltimore city, State of Maryland, have invented certain new and useful Improvements in Automatic Oil-Feed Devices, of which the following is a specification.

This invention relates to lubricating appliances for die-stocks to feed oil to the cutting ends of the chasers.

The invention has for its object to provide a novel and improved device of the kind stated which feeds oil in small measured quantities, and which is entirely automatic in operation, the feed being occasioned by the rotary movement of the die-stock when in use.

The object stated is attained by means of a combination and arrangement of parts to be hereinafter described and claimed, and in order that the same may be better understood, reference is had to the accompanying drawings forming a part of this specification.

25 In the drawings—

Figure 1 is an elevation of the device, partly in section, and in position on a die-stock; Figure 2 is a section on the line 2—2 of Figure 5; Figure 3 is a section on the line 3—3 of Figure 2; Figure 4 is a view similar to Figure 2 showing the device in inverted position; Figure 5 is a horizontal section on the line 5—5 of Figure 2, and Figure 6 is a cross-section on the line 6—6 of Figure 4.

Referring specifically to the drawings, 10 denotes a die-stock having end extensions 11 as usual for handles whereby the stock is rotated. The stock has a work-receiving 40 opening 12 into which the chasers 13 extend.

On the body of the stock 10 is mounted a device for automatically supplying oil to the cutting ends of the chasers 13. It will 45 be understood however that the device may also be mounted on any other portion of the stock in such a manner that the oil is fed to the proper place. The device is a fluid-tight receptacle 14 containing a supply of oil and 50 having an outlet into the opening 12 so that the oil is discharged on the work to lubricate the cutting ends of the chasers 13. The receptacle has a filler nipple 15 provided with a suitable closure. Ears 16 on the 55 receptacle 14 provide convenient means for

attaching the same to the stock by screws or other suitable fasteners 17.

The receptacle 14 is rectangular, and adjacent to one of its ends it contains two laterally spaced oil-collecting chambers 18, 60 with a bottom 19 common to both, but of less width than that of the chambers where it extends therebetween. That portion of the bottom wall which is between the chambers has upstanding side flanges 20 where- 65 by a trough is produced which connects the chambers. The chambers have inner and outer side walls 21 and 22, and end walls 23, the side walls extending transversely between the front and rear walls of the recep- 70 tacle 14. It will be noted that the walls 21 are spaced from the aforementioned end of this receptacle 14 (this being the top when the stock 10 is positioned as shown in Figure 1), and that the walls 22 extend down from said receptacle end to terminate short of the bottom 19 of the chambers. The space between the walls 22 defines a second chamber 24 which opens at its ends into the receptacle 14 through the space between the 75 front and rear walls thereof and the sides 20 of the trough connecting the chambers 18. The chambers 18 are in communication with the chamber 24 through the spaces between the bottom of the walls 22 and the 80 bottom 19 of the chambers 18. A direct communication between the interior of the receptacle 14 and the chambers 18 is had by the way of the open tops of the latter.

From the trough which extends between 85 the chambers 18 extends a short cylinder 25 which opens into said trough and slidably seats a plunger 26 having a head 27 which extends into the chamber 24 and is of sufficient weight to force the plunger down in 90 the cylinder when the parts are in the position shown in Figure 2.

From the bottom of the cylinder 25 extends a tube 28 which passes through that end of the receptacle which is at the bottom in Figure 2. This tube is the discharge tube which carries the oil into the opening 12 onto the work therein, its outer end being fitted with a suitable nozzle 28a.

In the tube 28 slidably seats a tubular 105 stem 29 extending from the plunger 26. This stem has side ports 30, 31 and 32 at different levels.

On the tube 28 are two diametrically opposite by-pass chambers 33, and near the 110

top and the bottom of said chambers the tube has side entrance and exit ports 34 and 35 through which communication is established between the by-pass chambers and the 5 interior of the stem 29.

From the flanges 20 rise guide rods 36 for the plunger 26, the opposite sides of the plunger head 27 having grooves to seat 10 said rods. The bottom of the plunger head has notches 37 to seat the flanges 20 when the plunger 26 is at the limit of its downward stroke.

The receptacle 14 is provided with an automatic air-vent valve 38.

15 The operation of the device may be summarized as follows—

As the receptacle 14 (containing a supply of oil) is attached to the die-stock 10, it swings around in a circular path when the 20 die-stock is in operation. This motion of the receptacle inverts the same once every revolution of the die-stock. Figure 4 of the drawings shows the device in inverted position. It will therefore be evident that the 25 plunger 26 is made to slide down into and out of the cylinder 25 as the device revolves with the die-stock. When the device is at the top, as shown in Figure 2, the plunger is down in the cylinder, and when the device 30 approaches the inverted position the plunger slides out of the cylinder as shown in Figure 4. This movement of the plunger is positive, due to the weighted head 27. The motion of the receptacle 14 causes the oil to 35 splash around therein and thus to flow into the trough from which the cylinder 25 extends, the oil passing over the top of the walls 21, and under the walls 22, as well as over the flanges 20. As the device passes 40 from the position shown in Figure 4 to the position shown in Figure 2, the cylinder 25 now being open, oil gathers in the same, and when the device approaches the position shown in Figure 2, the plunger 26 slides 45 down into the cylinder and forces the oil out of the same into the stem 29 through the ports 30 which open into the cylinder when the plunger is out of the same. The oil in the stem 29 however cannot escape directly 50 to the nozzle 28^a as the stem is closed up between the ports 31 and 32 as shown at 39, although it opens at its lower end into the tube 28. During the inward stroke of the plunger to the position shown in Figure 2, 55 the ports 31 pass the ports 34, whereupon oil is admitted to the by-passes 33 through these ports. During this stroke of the plunger the ports 32 also pass ports 35 at the bottom of the by-passes 33, and the oil flows 60 from the latter through said ports back into the lower end of the stem 29 from the open lower end of which it passes into the lower end of the tube 28 and is discharged through the nozzle 28^a onto the work. After the stock 65 10 has been turned a number of times the

oil is discharged in drops from the nozzle 28^a, one drop at every revolution of the stock around the work, the feed of oil being entirely automatic. The specific construction and arrangement of the oil-collecting chambers 18 and 24, and the trough therebetween assures a flow of oil to the cylinder 25. 70

I claim;

1. The combination with a die-stock operating with a rotary motion; of an oil-receptacle carried thereby, an oil-collecting chamber in the receptacle into which the oil is splashed by the motion of the die-stock, an outlet cylinder leading from the chamber, a feed tube leading from the cylinder, a reciprocatory plunger movable into and out of the cylinder by the motion of the die-stock, a hollow stem extending from the plunger and slidably seating in the tube, the outer end of said stem opening into the tube, and a by-pass having entrance and exit ports, the aforesaid tube having a port which opens into the cylinder when the plunger is out of the same and other ports for establishing communication between the interior of the 80 stem and the entrance and exit ports respectively of the by-pass. 90

2. The combination with a die-stock operating with a rotary motion; of an oil-receptacle carried thereby, an oil-collecting 95 chamber in the receptacle into which the oil is splashed by the motion of the die-stock, an outlet cylinder leading from the chamber, a feed tube leading from the cylinder, a reciprocatory plunger movable into and out 100 of the cylinder by the motion of the die-stock, a hollow stem extending from the plunger and slidably seating in the tube, and outer of said stem opening into the tube, and a by-pass having entrance and 105 exit ports, the aforesaid tube having a port which opens into the cylinder when the plunger is out of the same and other ports for establishing communication between the interior of the stem and the entrance and exit 110 ports respectively of the by-pass, said stem being closed between the last mentioned ports thereof.

3. The combination with a die-stock operating with a rotary motion; of an oil receptacle carried thereby, a pair of laterally spaced oil-collecting chambers mounted in the receptacle into which the oil is splashed by the motion of the die-stock, said chambers being located adjacent to one end of the 115 receptacle and having outer side walls spaced therefrom, and inner walls extending from said receptacle end wall and terminating short of the bottom of the chambers, a trough extending between the chambers and 120 open to the interior of the receptacle, and means for discharging oil from the trough. 125

4. The combination with a die-stock operating with a rotary motion; of an oil receptacle carried thereby, a pair of laterally 130

spaced oil-collecting chambers mounted in the receptacle into which the oil is splashed by the motion of the die-stock, said chambers being located adjacent to one end of the 5 receptacle and having outer side walls spaced therefrom, and inner walls extending from said receptacle end wall and terminating short of the bottom of the chambers, a trough 10 extending between the chambers and open to the interior of the receptacle, an outlet cylinder leading from the trough, a feed tube leading from the cylinder, a reciprocatory plunger movable into and out of the cylinder by the motion of the die-stock, a hollow 15 stem extending from the plunger and slidably seating in the tube, the outer end of said stem opening into the tube, and a by-pass having entrance and exit ports, the aforesaid tube having a port which opens into the cylinder when the plunger is out of the 20 same, and other ports for establishing communication between the interior of the stem and the entrance and exit ports respectively of the by-pass.

In testimony whereof I affix my signature. 25
WILLIAM H. WIX.
